UNITED STATES PATENT OFFICE.

HENRY G. FRENCH AND HERMAN J. H. HUBER, OF SCHENECTADY, NEW YORK, AS
SIGNORS TO GENERAL ELECTRIC COMPANY, A CORPORATION OF NEW YORK.

ELECTRIC SWITCH.

Application filed October 10, 1922. Serial No. 593,606.

To all whom it may concern:

Be it known that we, HENRY G. FRENCH and HERMAN J. H. HUBER, citizens of the United States, residing at Schenectady, county of Schenectady, State of New York, have invented certain new and useful Improvements in Electric Switches, of which the following is a specification.

Our invention relates to electric switches and more particularly to contact devices of the relatively movable cooperating type and has for an object to provide an improved contact device of such flexibility and construction as to insure that the relatively movable contacts register correctly for a surface to surface contact of maximum efficiency irrespective of niceties in alignment of the parts supporting the contacts.

Our invention will be better understood from the following description taken in connection with the accompanying drawing and its scope will be pointed out in the appended claims.

Fig. 1 is an elevation, with parts broken away, illustrating an embodiment of our invention, the supporting members of the relatively movable contacts being shown in alignment, Fig. 2 is an elevation similar to Fig. 1 but showing the supporting members of the contacts out of alignment, Fig. 3 is a plan, with parts broken away, of the embodiment of the invention shown in Figs. 1 and 2, and Fig. 4 illustrates an application of the embodiment of the invention shown in Figs. 1, 2 and 3 to a switch structure of the removable truck panel type shown in elevation.

In switch-gear embodying relatively movable cooperating contacts it is frequently difficult and often impractical to employ the refinements of construction and adjustments necessary to a precise alignment of the contact supporting structures so as to ensure that the contacts will register with that nicety essential to a highly efficient electric contact. Even though the refinements of construction and adjustments are carried to an extreme, the complex structure of modern switchgear, the inevitable wear of the parts, shocks and jars of operation which disturb the adjustments, and other causes make it very troublesome and difficult particularly in contact devices of the plug and socket type and especially when heavy currents have to be carried

to obtain an efficient surface to surface contact principally because of variations and inaccuracies in the alignment of the contact supporting structures. According to our invention, we provide an improved construction of contacts which obviates this difficulty and renders unnecessary the refinements of construction requisite to a precise alignment of the contact supporting structures and therefore provides a more economical and efficient construction which is capable of withstanding relatively hard use.

In the figures of the accompanying drawing, we have illustrated an embodiment of our invention in an electric switching or disconnecting device of the plug and socket type comprising relatively movable cooperating contacts, one of which may be fixed. The fixed contact member is shown as the socket part of the switching device and may comprise a portion or terminal 1 which, for purposes of illustration, may be secured by a clamping member 2 and bolts 3 to a bus bar structure comprising spaced bus bars 4 separated by spacers 5, the bus bar structure being supported by insulators 6 secured to any suitable supporting means or framework 7, see Fig. 4. The terminal 1 is provided with a plurality of spaced jaws or contact members 8, the ends of which are preferably curved outward to form a flaring passage way or mouth in order better to receive and guide the engaging parts of the cooperating contact.

Our invention particularly resides in the contact device which constitutes the plug part of the electric switching device and is herein shown as the cooperating movable contact. The contact device comprises a terminal member 9 which may be provided with a conducting stud or shank 10 shown as extending through an insulator 11 which may be secured to a movable structure such as a truck 12, see Fig. 4, or if used in circuit breaker construction, the contact device may be mounted in a manner well known to the art. Pivotaly associated with the terminal 9 on opposite sides thereof on pivot pins 13 are supporting members such as plates 14 which serve to support or carry the parts of the contact device which cooperate with and engage the jaws 8 of the fixed contact. Mounted on the plates 14 and extending transversely thereof is a supporting member

such as a rod or pin 15 on which is mounted between the plates 14, a lever or equalizing bar 16.

In order to provide a rigid assembly of the plates 14 so that the plates cannot twist or move relatively to each other and to hold the bar 16 in place, the rod 15 may be provided with spacers such as sleeves 17 between the plates 14 and the bar 16 and may also have its ends threaded to receive nuts 18 for rigidly clamping the assembly, the ends of the rod 15 being spun over the nuts 18 to prevent them from working loose, or the nuts otherwise secured in any suitable manner. In order that the plates 14 may normally be held in alignment with the terminal 9, as for example when the cooperating contacts are not in engagement, suitable resilient means is provided such as compression springs 19 mounted between the terminal 9 and the bar 16 and arranged to exert forces on the bar 16 adjacent the ends thereof tending to align the plates 14 with the terminal 9. For centering and maintaining the springs 19 in position, the equalizing bar 16 may be provided with suitable projections or lugs 20. The springs 19, the equalizing bar 16 and the shaft 15 therefore tend to maintain the plates 14 in alignment with the terminal 9 and also allow movement of the plates 14 relatively to the terminal 9. Loosely mounted on the plates 14 so as to be movable relatively thereto and independently of each other are contact members or fingers 21 which are adapted to engage the jaws 8 of the terminal 1. The nose or outer end of the contact fingers is curved inwardly in order to guide the contact fingers into engagement with the flaring mouth of the jaws 8 and to ensure the register of the contact fingers with the jaws 8 when the supporting structures of the relatively movable contacts are not in alignment as shown in Fig. 2. Each of the contact fingers 21 may comprise a single member providing the necessary contact area or a plurality of narrow contact fingers arranged in sets, as is more clearly shown in Fig. 3, the latter arrangement being preferable as it provides a more flexible structure and therefore insures a better electric contact. The contact fingers 21 may be connected to the terminal 9 by any suitable conducting means such as flexible connectors or leads 22 which may be secured to the terminal 9 in any suitable manner such as by plates 23 and bolts 24 and riveted, brazed or otherwise secured to the contact fingers 21.

With this arrangement the outer bolts 24 may be used to lock the pivot pins 13 from turning, the shanks of the bolts interlocking for example with the concave inner ends of the pivot pins 13 which are screwed into the terminal 9. For loosely mounting the contact fingers 21 on the plates 14, the fingers

may be provided with supporting members or brackets 25 and may be supported between the plates 14 by spaced pins 26 extending through the brackets 25 between the plates 14 and through slots 27 therein which permit movement of the pins 26 and therefore of the contact fingers 21 independently of each other and of the plates 14. Each contact finger or set of contact fingers is preferably supported on at least two of the pins 26. Suitable resilient means, such as compression springs 28, are mounted between the contact fingers 21 and intermediate the pins 26 supporting each contact finger or set of fingers to spread the contact fingers apart and when the contacts are not in engagement, the contact fingers are moved to their limit of travel which is determined by the pins 26 coming to rest against the outer ends of their respective slots. The springs 28 may be centered and maintained in position by suitable means such as lugs 29 on the brackets 25. The spacing of the slots and the length thereof is such that the contact fingers 21 may be spaced apart a distance relatively greater than the distance between the contact jaws 8 in order that upon engagement of the contact fingers 21 with the jaws 8, the fingers may be readily deflected by the jaws and also that there may be a substantial pressure between the engaging parts of the cooperating contacts. It is therefore obvious that the construction is such that the compression springs 28 can be made to exert a very considerable pressure against the contact fingers 21 so as to insure a firm and positive contact with the jaws 8.

With this construction and arrangement of parts, it is obvious that if the supports of the cooperating contacts are in alignment as shown in Fig. 1 the springs 19 will hold the plates 14 in alignment with the terminal 9 and the contact fingers 21 will enter the flared jaws 8 and be forced together against the pressure of the springs 28 so as to insure a good surface to surface contact. If, however, the contact supporting structures are not in alignment as shown in Fig. 2, the contact fingers 21 will engage the jaws 8 at an angle and will therefore be canted into alignment with the jaws 8 so as to register therewith for a surface to surface contact since the lost motion mounting of the contact fingers 21 permits them to rock freely relatively to the plates 14. At the same time assuming the contact supports considerably out of alignment, two diagonally opposite pins 26, the upper left and lower right hand pins as shown in Fig. 2, reach the limit of travel in their respective slots and the plates 14 will be turned upwardly as shown in Fig. 2 against the action of the springs 19. Each of the contact fingers 21 is thus maintained free to rock or turn about a single point,

that is one of its supporting pins 26 and the contact finger is therefore, under the action of springs 28, maintained in surface to surface contact with its cooperating jaws 8.

5 When the contacts are separated or disengaged the springs 19 acting on the equalizing bar 16 turn the plates 14 into alignment with the terminal 9 and the springs 28 spread the contact fingers 21 apart until the

10 pins 26 bear against the outer ends of their respective slots.

In Fig. 4 we have illustrated a switch gear structure to which our invention is particularly adapted. This structure is known to the art as the removable truck panel type and comprises a housing or cubicle 30 and a truck 12 arranged to be rolled into and out of the housing 30. Mounted in the housing 30 at the rear thereof and on a supporting frame 7 are the distributing bus bars 4 mounted on insulators 6 and having terminals 1 with jaws 8 comprising the fixed contact as shown in Figs. 1 and 2. The particular arrangement shown is for a three phase alternating current system. Similar fixed contacts 8' are mounted in a row within the housing 30 beneath the bus bars 4 and to these contacts are connected incoming leads 31. Mounted on the rear of the truck structure are insulators 10 supporting contact devices embodying our invention as shown in Figs. 1, 2 and 3. As the truck 12 is moved into the housing 30, the contact devices 9 thereon engage the fixed contacts 8, 8'. The fixed contacts 8, 8' are preferably made the live contacts, because of their extreme simplicity of construction and therefore slight probability of getting out of order. The contacts 9 embodying our invention are of more complex structure, and by making them the movable contacts, they are dead when the truck 12 is removed and are therefore conveniently and safely accessible for inspection and repairs. The truck has mounted thereon a suitable circuit breaker 32 arranged to be controlled by an operating mechanism 33 to complete a circuit from the movable contacts 9 connected to the fixed contacts 8' of the incoming leads 31 to the distribution bus bars 4 by means of suitable leads 34. Suitable auxiliary devices for operating relays, measuring and indicating instruments, etc., which may be mounted on the truck panel, such as current and potential transformers 35 and 36 respectively are also mounted on the truck.

With switch gear structure of the type illustrated in Fig. 4, it will be obvious that if the disconnecting or contact devices are of such construction as to necessitate a precise alignment of the contact supporting structures, an inordinate amount of time and labor is necessary to accomplish the requisite refinements of adjustment. Moreover, as

the truck panels are generally made interchangeable and as it is frequently desirable to provide spaces, slight variations in the adjustments of the mountings increase the difficulty. Also dirt or other foreign matter either on or under the truck wheels results in misalignment of the contact supporting structures. Furthermore the switch gear is subject to a certain amount of more or less hard use in operation and this tends to disturb any refinements in adjustment. By the use of contact devices embodying our invention however the necessity of such nicety of adjustment of the contact supporting structures is eliminated as the flexible construction of the contact device 9 permits considerable leeway with respect to the alignment of the contact supporting structures. This reduces cost and simplifies operation and ensures that the cooperating contacts will register with that surface to surface engagement which is requisite to an efficient electric contact. In the arrangement shown, the contact device 9 eliminates difficulties due to the contact supporting structures being vertically out of alignment. In order to provide for lateral or side play of the truck 12, that is to say when the contact supporting structures are out of alignment horizontally, the jaws 8 of the fixed contact may be made wider than the contact fingers 21, that is to say the width of the movable contact.

What we claim as new and desire to secure by Letters Patent of the United States, is,—

1. A contact device comprising a terminal member, supporting members pivotally associated therewith, resilient means for normally maintaining said supporting members in alignment with said terminal member and arranged to allow movement of said supporting members relatively to the terminal member, a plurality of contact fingers loosely mounted on said supporting members and independently movable relatively thereto, and resilient means arranged to spread said fingers apart.

2. A contact device comprising a terminal, supporting members pivotally associated therewith, an equalizing member supported by said supporting members, resilient means affecting said equalizing member normally to maintain said supporting members in alignment with said terminal and arranged to allow movement of said supporting members relatively to said terminal, contact fingers carried by said supporting members and independently movable relatively thereto, and resilient means arranged to spread said fingers apart.

3. A contact device comprising a terminal, two plates pivotally associated with said terminal on opposite sides thereof, an equalizing bar mounted between said plates and supported thereby, resilient means exerting

- forces on the ends of said bar tending to maintain said plates in alignment with said terminal and arranged to allow movement of said plates relatively to said terminal, a pair of contact fingers loosely mounted on and supported by said plates for movement relatively thereto, and resilient means arranged to spread said fingers apart, the construction and arrangement of parts being such as to provide for movement of said contact fingers relatively to said plates independently of each other.
4. A contact device comprising a terminal, two plates pivotally associated with said terminal on opposite sides thereof, an equalizing bar mounted between said plates and supported thereby, resilient means mounted between said bar and said terminal arranged to exert forces on said bar tending to maintain said plates in alignment with the terminal and adapted to allow movement of said plates relatively to the terminal, a plurality of pins extending between said plates and through spaced slots therein, a pair of contact fingers each supported by at least two of said pins, resilient means between said contact fingers arranged to spread the same apart and flexible conducting means connecting said fingers to said terminal, the construction and arrangement of parts being such that each of said fingers is adapted to be moved independently of the other and of said plates.
5. A contact device comprising a terminal, two plates pivotally associated with said terminal on opposite sides thereof, an equalizing bar mounted between said plates and supported thereby, resilient means mounted between said bar and said terminal arranged to exert forces on said bar tending to maintain said plates in alignment with the terminal and adapted to allow movement of said plates relatively to the terminal, a pair of contact fingers loosely mounted on and supported by said plates for movement relatively thereto independently of each other, flexible conducting means connecting said fingers to said terminal, and resilient means arranged to spread said contact fingers apart.
6. A contact device comprising a terminal, two plates pivotally associated with said terminal on opposite sides thereof, an equalizing bar mounted between said plates and supported thereby, resilient means mounted between said bar and said terminal arranged to exert forces on said bar tending to maintain said plates in alignment with the terminal and adapted to allow movement of said plates relatively to the terminal, a plurality of contact fingers arranged in two sets loosely mounted on and supported by said plates for movement relatively thereto independently of each other, flexible conducting means connecting said fingers to said terminal, and resilient means arranged to spread said sets of contact fingers apart.
7. An electric switching device comprising a contact member having two jaws and a cooperating contact member movable relatively to said first contact member comprising a terminal, two plates pivotally associated with said terminal on opposite sides thereof, an equalizing bar mounted between said plates and supported thereby, resilient means exerting forces on the ends of said bar tending to maintain said plates in alignment with said terminal and arranged to allow movement of said plates relatively to the terminal, a pair of contact fingers loosely mounted on said plates for movement relatively thereto independently of each other, and resilient means tending to spread said contact fingers apart, whereby upon movement of one of said contact members into engagement with the other, said contact fingers will register with said jaws irrespective of the alignment of said jaws and said terminal.

In witness whereof, we have hereunto set our hands this 9th day of October, 1922.

HENRY G. FRENCH.
HERMAN J. H. HUBER.
